Primary Examiner—Cathron B. Matta
Attorney, Agent, or Firm—Richard B. O'Planick[57] **CLAIM**

The ornamental design for a canister lid, as shown and described.

DESCRIPTION

FIG. 1 is a top right front perspective view of a canister lid showing our new design;

FIG. 2 is a top plan view thereof, shown at an enlarged scale;

FIG. 3 is a rear elevational view thereof, shown at an enlarged scale; the front elevational view being substantially a mirror image;

FIG. 4 is a left side elevational view thereof, shown at an enlarged scale;

FIG. 5 is a right side elevational view thereof, shown at an enlarged scale; and,

FIG. 6 is a bottom plan view thereof, shown at an enlarged scale.
